UNITED STATES PATENT OFFICE.

MICHAEL F. SCHOPF AND LOUIS J. CHRISTIANSON, OF CHICAGO, ILLINOIS.

ANTISKID DEVICE.

1,375,735.

Specification of Letters Patent. Patented Apr. 26, 1921.

Application filed April 21, 1920. Serial No. 375,571.

To all whom it may concern:

Be it known that we, MICHAEL F. SCHOPF and LOUIS J. CHRISTIANSON, citizens of the United States, residing at Chicago, in the county of Cook and State of Illinois, have invented certain new and useful Improvements in Antiskid Devices, of which the following is a description.

Our invention belongs to that general class of devices known as anti-skid devices adapted to be used on vehicle wheels in order to prevent skidding, to increase the traction and to prevent the wheels spinning. The invention has among its objects the production of a device of the kind described that is simple, convenient, durable, reliable, efficient, inexpensive and satisfactory for use wherever found applicable. It has particularly as an object the production of a device that will not in any way cause excessive wear on a tire, and which will be particularly efficient and durable under all conditions. Many other objects and advantages of the construction herein shown and described will be obvious to those skilled in the art from the disclosure herein given.

To this end our invention consists in the novel construction, arrangement and combination of parts herein shown and described and more particularly pointed out in the claims.

In the drawings, wherein like reference characters indicate like or corresponding parts,

Figure 1 is a view in elevation of a wheel with our device applied thereto;

Fig. 2 is a top plan view of the same;

Fig. 3 is a sectional view taken substantially on line 3—3 of Fig. 1;

Fig. 4 is a plan view of one of the pads; and

Fig. 5 is a sectional view taken substantially on line 5—5 of Fig. 4.

Referring to the drawings, in which the preferred form of our device is shown, 1—1 etc., represent a series of pads or tread members which are suitably attached together and mounted upon a wheel and form a tread therefor. Each of the treads is preferably constructed of strands of wire, each strand of which is made up of a plurality of small strands, the parts being suitably secured together so as to substantially form an integral or one-part structure. As most clearly shown in Figs. 4 and 5, 2 and 3 rep-

resent strands extending lengthwise and woven together in any desired manner, 4 being preferably a cross-strand which may be flattened out and which is woven in between 60 the strands 2 and 3.

The various strands are suitably secured together at the ends of the pad, for example, by welding or otherwise securing the ends 5 thereto. When constructed, each pad, 65 while to a certain extent flexible and made up of many surfaces, is substantially in one part. As shown, each pad is provided with the desired number of fastening members or links 6, which are preferably looped as at 70 7—7 around one of the strands 2 at each side, or 3, as the case may be, depending upon which strand is at the under side, the same being connected to links 8—8 which connect with the side chains 9—9 of suitable 75 construction.

We have illustrated the wheel felly 11, as for example in an automobile wheel, upon which is arranged a rim 12 of suitable form and construction arranged to coöperate with 80 the casing 13, within which may be arranged the inner tube 14 or the equivalent. The particular wheel, rim and tire construction forms no part of the present invention. We secure the circumferential chains 9 to the 85 wheel at the desired number of points by straps 15 or the equivalent, which may be provided with buckles 16 so that the device may be securely locked on the wheel.

The ends of the chains 9 may be connected by links 17 or the equivalent. The device is applied substantially as shown in Figs. 1, 2 and 3, and secured by the straps or the equivalent, as previously mentioned. With this construction, it will be noted that 95 each pad has a considerable bearing on the casing, and consequently does not have the same tendency to cut or injure the casing as where cross-chains are employed. The ends at the inner side may be rounded substantially as indicated at 18 of Fig. 5, but the ends at the outer sides are preferably left sharp, as indicated at 19, so as to cut into ice, snow and frozen ground. The pad has considerable wearing face, consequently the 100 same is of extremely long life. Being made out of steel or light wire, in the form of a fabric, a considerable portion of the same may wear away without in any ways impairing its efficiency. As a matter of fact, the 110 same may wear down substantially to the

tire and still give satisfactory service, or substantially so, until it is completely used up, at which time the same may be renewed. Obviously, by covering a considerable portion of the tire, the same to a large extent prevents punctures, and it has been found that the same has a tendency to prevent blow-outs, as it is substantially a reinforcement to the casing. While we prefer to 10 use the straps 15, or the equivalents, very satisfactory results are obtained without the straps.

Having thus described our invention, it is obvious that various immaterial modifications may be made in the same without departing from the spirit of our invention; hence we do not wish to be understood as limiting ourselves to the exact form, construction, arrangement and combination of 20 parts herein shown and described except as defined by the appended claims, or uses mentioned.

What we claim as new and desire to secure by Letters Patent is:

- 25 1. An anti-skid device consisting of a plurality of anti-skid pad members, each having a suitable frame provided with side portions, and a plurality of woven wire strands secured in said side portions, said strands 30 being arranged whereby they cross one an-

other, and cross strands interposed between said first mentioned woven strands.

2. An anti-skid slipping pad having a suitable base and side portions secured thereto, woven wire strands secured to said side portions and extending longitudinally of the base, each of said woven strands at one end being secured to the lower portion of one side, while the opposite end is secured to the upper portion of the other side of 35 the base, and transverse strands extending across said base beneath said longitudinal woven strands.

3. An anti-skid device comprising a plurality of anti-skid pads adapted to be disposed around a tire, each of said pads having a base provided with sides, a plurality of wire strands secured to the sides of each pad, said strands being constructed to cross 40 one another, and means for securing the 50 pads to the tire.

In testimony whereof, we have hereunto signed our names in the presence of two subscribing witnesses.

MICHAEL F. SCHOPF.
LOUIS J. CHRISTIANSON.
